COMBINED TELEVISION CABINET AND BASE OR SIMILAR ARTICLE

Joseph D. Portanova, Arcadia, Calif., assignor to Hoff-
man Radio Corporation, a corporation of California

Application June 15, 1953, Serial No. 25,487

Term of patent 14 years

(Cl. D56—4)

To all whom it may concern:

Be it known that I, Joseph D. Portanova, a citizen of the United States of America, residing at Arcadia, in the county of Los Angeles, State of California, have invented a new, original, and ornamental Design for a Combined Television Cabinet and Base or Similar Article of which the following is a specification, reference being had to the accompanying drawing, forming a part hereof.

Figure 1 is a front elevational view of a combined television cabinet and base or similar article, showing my new design;

Figure 2 is a side elevational view thereof;

Figure 3 is a front elevational view thereof showing the doors of the cabinet in open position; and,

Figure 4 is a perspective view thereof showing the doors of the cabinet in open position.

The dominant feature of my design resides in the full line portion of the drawing. The rear of the television cabinet is plain.

I claim:

The ornamental design for a combined television cabinet and base, or similar article, substantially as shown and described.
